UNITED STATES PATENT OFFICE

116,222

DESIGN FOR A SPRAYER OR SIMILAR ARTICLE

Harvey C. J. Eick, Sheboygan Falls, and Christian
Behrens, Sheboygan, Wis.

Application January 30, 1939, Serial No. 82,668

Term of patent 3½ years

To all whom it may concern:

Be it known that we, Harvey C. J. Eick and Christian Behrens, citizens of the United States, of Sheboygan Falls and Sheboygan, respectively, in the county of Sheboygan and State of Wisconsin, have invented a new, original, and ornamental Design for a Sprayer or Similar Article, of which the following is a specification, reference being had to the accompanying drawing, forming part thereof.

Figure 1 is a side elevation of the sprayer or similar article, showing our new design, and

We claim:

The ornamental design for a sprayer or similar article, as shown.

HARVEY C. J. EICK.
CHRISTIAN BEHRENS.
